DRINKING VESSEL OR THE LIKE

Lajos Bencik, 19 Melmore Gardens,
East Orange, N.J. 07018

Filed Mar. 2, 1970, Ser. No. 21,692

Term of patent 14 years

Int. Cl. D7—01

U.S. Cl. D36—8

FIG. 1

FIG. 4

FIG. 7

Des. 222,375

PAGE 2

FIG. 3

FIG. 2

FIG. 6

FIG. 5

FIG. 1 is a perspective view of a drinking vessel, or the like, showing my new design;

FIG. 2 is a top plan view thereof;

FIG. 3 is a sectional view on line 3—3 of FIG. 2;

FIG. 4 is a bottom plan view;

FIG. 5 is a top plan view of a drinking vessel, or the like, showing another form of my new design wherein the outer skirt portion terminates above the bottom of the container portion;

FIG. 6 is a sectional view thereof on line 6—6 of FIG. 5; and

FIG. 7 is a bottom plan view thereof.

I claim:

The ornamental design for drinking vessel or the like, as shown and described.
